UNITED STATES PATENT OFFICE.

ANTHONY GRAF, OF SYRACUSE, NEW YORK.

PISTON-HOLDING DEVICE.

Application filed November 23, 1926. Serial No. 150,217.

This invention has for its object a particularly simple and efficient device or tool for holding pistons or for taking hold of pistons of various sizes so that they can be held in a 5 vise or other apparatus for the purpose of working on or repairing the same.

The invention consists in the novel features and in the combinations and constructions hereinafter set forth and claimed.

10 In describing this invention, reference is had to the accompanying drawings in which like characters designate corresponding parts in all the views.

Figure 1 is a plan view of this piston holder.

Figure 2 is a transverse sectional view, the contiguous portion of the jaws of a vise being shown in sections and the piston being indicated in dotted lines.

20 This piston holding device comprises body sections which are substantially flat and provided on one side thereof with a plurality of circular series of jaws for engaging the piston at spaced apart points, the sections having 25 projections on the opposite side thereof for entering between the jaws of a vise, these projections being preferably movably fastened together and also preferably, a spring is interposed between them tending to separate them.

30 1 designates the body sections which are semi-discoidal in general form.

2 are the spaced apart jaws, there being 35 preferably three jaws in each series so that the piston 3 is engaged at three points. Also, the sections 1 are provided on the side thereof formed with the jaws with a recess 4 for accommodating or forming a clearance for projections that might be on the head of the 40 piston.

The semi-discoidal sections 1 are provided with opposing flat faces, these flat faces being provided on diametrically extending flanges located on the opposite sides of the sections to 45 those on which the jaws are located. That is, assuming that the jaws are arranged on

the upper sides of the sections as shown, the flanges are located on the lower side of the sections. The flanges are preferably connected together and as here shown, one of 50 them as the flange 5 is formed with a laterally extending hinge leaf 7 extending over the edge of the other flange 6 and between lugs or leaves 8 on the flange 6, and a hinge pin 9 extends through the lugs and the leaf, this 55 hinge pin being preferably a loose fit so as to permit a somewhat rectilinear movement of the sections toward and from each other, particularly toward each other when the jaws 10 of a vise are clamped toward each other. 60

Preferably, a spring 11 is interposed between the flange which tends to separate the sections 1. Also, sufficient clearance is provided at 12 at the end of the hinge leaf 7 to permit the pivotal or relative movement of 65 the flanges toward each other when they are clamped between the jaws of the vise.

In operation, these tools are made to fit pistons of various sizes and the piston is placed with its head end between one series 70 of jaws 2 and then the piston holder placed between the jaws of the vise and the jaws tightened on the flanges 6, 7 thus snugly holding the piston so that a workman can work on the same. Obviously, the tool may be 75 made with only one series of jaws 2.

What I claim is:

A piston holding device comprising semi-discoidal body sections formed with a plurality of spaced apart piston engaging jaws 80 on one side thereof, opposing flanges extending diametrically of the sections respectively and located on the opposite sides of the sections to those on which the jaws are located, the flanges being opposed to each other and 85 adapted to be received between the jaws of a vise.

In testimony whereof, I have hereunto signed my name, at Syracuse, in the county of Onondaga, and State of New York, this 17th 90 day of November, 1926.

ANTHONY GRAF.
